UNITED STATES PATENT OFFICE

114,972

DESIGN FOR AN AIRPLANE

Berthoud C. Boulton, Towson, and Lewis C. McCarty, Jr., Baltimore, Md., assignors to The Glenn L. Martin Company, Baltimore, Md.

Application January 21, 1938, Serial No. 74,456

Term of patent 14 years

To all whom it may concern:

Be it known that we, Berthoud C. Boulton and Lewis C. McCarty, Jr., citizens of the United States and residents, respectively, of Towson, in the county of Baltimore and State of Maryland, and of Baltimore, in the State of Maryland, have invented a new, original, and ornamental Design for an Airplane, of which the following is a specification, reference being had to the accompanying drawings, forming part thereof.

Figure 1 is a perspective view of the subject airplane in flight,

Figure 2 is a front elevational view of the airplane shown in Figure 1,

Figure 3 is a side elevational view of same, and Figure 4 is a plan view.

We claim:

The ornamental design for an airplane, substantially as shown.

BERTHOUD C. BOULTON.
